INSULATING TERMINAL FOR NEON TUBES

Roy C. Baker, Denver, Colo.

Application February 26, 1937, Serial No. 127,865

7 Claims. (Cl. 176—126)

This invention relates to an insulating terminal for neon sign tubes.

One of the greatest sources of trouble in the present neon signs results from the break-down of the terminals of the tube at the point where they pass through the metal sign face. Ordinarily, the tubes are insulated from the sign face at this point by the porcelain bushings. These bushings become covered with carbon deposits from the atmosphere and, especially when wet, will cause the tubes to discharge across or through the bushings to the sign face, thus causing the break-down of the tubes at this point.

The principal object of the present invention is to provide an insulating terminal for neon tubes which can not be subject to "shorting" by moisture, atmospheric deposits, etc., and which will avoid the serious service troubles at present encountered with the tube terminals.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:—

Fig. 1 is a view illustrating the sign face in section with a tube terminal passing therethrough. In this view, the terminal has also been shown in section.

Fig. 2 is a perspective view illustrating the complete tube terminal as furnished, ready for welding to the sign tube.

In Fig. 1, the sign face is indicated at 10 and the neon tube at 11. In the usual sign construction, the tubes 11 are held spaced from the sign face 10 by means of the glass posts 12 to which the tubes are tied by means of tie wires 13 or in any other desired manner. The posts fit into attachment clips 14 which are bolted or otherwise secured to the supporting sign face 10.

The invention contemplates forming a terminal or extremity on the tube 11 which will allow the current to be conducted from the interior of the sign through the sign face 10 into the sign box without liability of electrical break-down at this point.

This is accomplished by welding a terminal such as shown in Fig. 2 to the extremity of the tube 11 and allowing this terminal to extend

through the hole in the sign face which is usually provided for the porcelain insulating bushing.

The terminal comprises a central glass tube 15, one extremity of which is welded to the extremity of the neon tube 11 as indicated by the weld line 21. The tube 15 contains the usual electrode, such as illustrated at 16, and is sealed at its outer extremity as shown at 17 about the conductors 18 which supply the current to the tube.

The central tube 15 is surrounded by an outer 10 glass tube 19 of greater diameter. The outer tube 19 is welded to the central tube as shown at 20 at its forward extremity and is preferably left open at its rearward extremity as illustrated. When installed, the open rearward extremity is spaced 15 a considerable distance from the metal sign face and is of course, protected by the enclosing box of the sign.

It can be readily seen that rain, snow, soot, 20 dust, etc., on the exterior of the sign cannot create an electric path to the conductors 18 or the inner electrode tube 15. Should moisture leak through the sign face it would simply moisten the outer surface of the outer tube and spread the electrical potential so that danger of a concentrated 25 "break down" spark would be lessened. The moisture could not possibly bridge the air gap between the outer and inner tubes.

It is well known that air is one of the best of 30 insulating mediums and the cylinder of air which surrounds the electrode tube provides a highly efficient insulating shield.

The terminals are furnished to the sign manufacturers as the complete unit of Fig. 2, with the two tubes and electrode in place, ready for welding to the neon tube extremity. The particular type of electrode as illustrated, is not important as the invention is equally valuable with any type of electrode.

While a specific form of the improvement has 40 been described and illustrated herein, it is desired to be understood that the same may be varied, within the scope of the appended claims, without departing from the spirit of the invention.

Having thus described the invention, what is 45 claimed and desired secured by Letters Patent is:—

1. An insulating terminal for a neon tube comprising: an inner electrode tube open at its one extremity and sealed at its other extremity; and 50 an outer insulating tube welded to said inner tube adjacent the open extremity of the latter, the other extremity of said outer tube being open for its full diameter about the sealed extremity of said inner tube.

2. An insulating terminal for a neon tube comprising: an inner electrode tube arranged at its forward extremity for welding to the extremity of said neon tube and sealed at its rearward extremity; an electrode within said inner tube; conductors extending from said electrode through the sealed extremity of said inner tube; and an outer tube of larger diameter than said inner tube and welded to the latter towards the forward extremity thereof so as to be maintained in spaced relation about said inner tube, said outer tube being open about the inner extremity of said inner tube.
3. Means for insulating a neon tube at the point where the latter passes through a metal sign face comprising: a tubular extremity on said neon tube, said extremity extending through an opening in said sign face; an outer glass tube of larger diameter surrounding said extremity at the point where the latter passes through said sign face, said outer tube being permanently welded to said extremity exteriorly of said sign face and being open about said extremity interiorly of said sign face, said tubular extremity projecting through the open extremity of said outer tube.
4. In a luminescent sign of the type in which a tube terminal extends horizontally through an opening in a sign face, means for insulating said terminal at the point of passage through said sign face comprising: a horizontal glass sleeve of larger diameter than said tube terminal, said sleeve being welded about said tube terminal on the exterior side of said sign face to form a unitary construction for supporting said sleeve in horizontal coaxial relation about said tube terminal through said sign face, the inner extremity of said sleeve being entirely open, said tube terminal projecting through the open extremity of said sleeve supported only by its welded forward extremity.
5. In a luminescent sign of the type in which a tube terminal extends horizontally through an opening in a sign face, means for insulating said terminal at the point of passage through said sign face comprising: a horizontal glass sleeve of larger diameter than said tube terminal, said sleeve being welded about said tube terminal on the exterior side of said sign face to form a unitary construction for supporting said sleeve in horizontal coaxial relation about said tube terminal through said sign face, the inner extremity of said sleeve being entirely open and spaced about the inner extremity of said tube terminal.
6. In a luminescent sign of the type in which a tube terminal extends horizontally through an opening in a sign face, means for insulating said terminal at the point of passage through said sign face comprising: a horizontal glass sleeve of larger diameter than said tube terminal, said sleeve being welded entirely around said tube terminal on the exterior side of said sign face to form a permanent union therewith for supporting said sleeve in horizontal coaxial relation about said tube terminal through said sign face, the inner extremity of said sleeve being entirely open, said tube terminal projecting through the open extremity of said sleeve supported only by its welded forward extremity.
7. An insulating terminal for a neon tube comprising: an inner electrode tube open at its one extremity and sealed at its other extremity; and an outer insulating tube sealed to said inner tube adjacent the open extremity of the latter, the other extremity of said outer tube being open for its full diameter about the sealed extremity of said inner tube.
